UNITED STATES PATENT OFFICE.

WILLIAM HAROLD MOSLEY, OF TORONTO, ONTARIO, CANADA.

DENTAL INSTRUMENT.

1,115,718.

Specification of Letters Patent.

Patented Nov. 3, 1914.

Application filed November 21, 1913. Serial No. 802,310.

To all whom it may concern:

Be it known that I, WILLIAM H. MOSLEY, a citizen of Canada, residing in Toronto, in the county of York, Province of Ontario, 5 Canada, and a British subject, have invented a certain new and useful Dental Instrument, of which the following is a specification.

This invention is a dental instrument and relates more particularly to the "hand-piece," which is designed as a device in 10 which a bit or tool is secured and by which the tool is manipulated in performing dental work.

An object of this invention is to provide 15 a hand instrument which can accommodate various bits or tools which have heretofore been manufactured as a number of separate instruments, and thereby require less storage space, and lessen the cost of implements.

Another purpose of the invention is to 20 provide a hand instrument, wherein various tools, such as burnishers, chisels, excavators, wrenches and the like, may be inserted in a single handpiece and secured at any desired angle with reference thereto, and thereby facilitate their manipulation.

The handpiece is characterized by a handle having a reduced adjustable end provided with locking means. A sleeve is 25 adapted to be positioned over this reduced end and to be adjustable thereon, the sleeve having a socket for a spherical tool-carrying member, the sleeve being provided with means to bring the spherical member into 30 engagement with locking means on the reduced end of the handle to maintain the spherical member in a predetermined position with relation to the handle.

One embodiment of the invention is illustrated in the accompanying drawings, in which—

Figure 1 is a side elevation of a handpiece constructed in accordance with the invention. Fig. 2 is a side elevation with the 45 retaining sleeve and spherical tool carrying member removed. Fig. 3 is an enlarged detail view of the retaining sleeve. Fig. 4 is an enlarged detail view of the spherical tool carrying member, showing grooves 50 formed in its surface. Fig. 5 is a detail sectional view of the upper or threaded end of the hand-piece, showing projections to engage the recesses or grooves on the spherical member of Fig. 4.

In the embodiment of the invention illustrated in the drawings, the handle, 1, may be

provided with a polygonal surface to prevent the instrument from rolling on an inclined surface. One end of the handle may be reduced, as at 2, and provided with 60 external threads 3. The free end of the handle 1 is preferably slightly concave, and may be provided with suitable retaining means 4.

A sleeve, 5, provided with a roughened surface, 6, is adapted to engage the threaded end 3 of the handle, the sleeve being internally threaded to permit the adjustment of the sleeve on the handle. The sleeve 5 is opened at one end to permit of the insertion of the threaded end of the handle, and it is 65 partially closed at its other end 7. At the end 7, the sleeve may be provided with a socket and a slot 8, which extends from the partially opened end 7 down into a side wall of the sleeve.

Loosely mounted within the sleeve 5 is a spherical member 9 which is shown provided with a tool engaging projection 10 adapted to pass between the walls of the slot 8 of the sleeve. A longitudinal passage 11 may be formed through the member 9 and projection 10, into which may be inserted an end of a dental instrument, such as a chisel, excavator, burnisher, wrench, and the like, and this passage 11 may be threaded or 70 provided with any other suitable retaining means to hold the tool in position on the member 9.

The outer surface of the member 9 may be roughened or scored, as at 12, whereby 75 when the sleeve 5 is adjusted by the finger part 6, on the handle end 3, toward the handle 1, the spherical member 9 may be clamped between the end 4 of the handle 1 and the end 7 of the sleeve 5, the roughened 80 surface 4 engaging the roughened surfaces 12 of the member 9 and serving to retain said member 9 against movement with relation to the handle. This invention will 85 permit a dentist to provide a single handpiece with a number of hand-operated tools, which can be retained at various angles with relation to the handpiece.

Having thus described my invention, what I claim as new and desire to secure by Letters Patent, is:

1. A dental handpiece comprising a handle, a sleeve mounted on the handle to cooperate with one end thereof, and a spherical tool carrying member positioned in the 100 sleeve and adapted to be firmly held between the end of the handle and an end of the

sleeve to retain a dental tool in a predetermined position with relation to the handle.

2. A dental handpiece comprising a handle having a reduced threaded end, an internally threaded sleeve adapted to engage said end of the handle, said sleeve being provided with a socket near one end thereof, a spherical tool-carrying member mounted for substantially universal movement in the socket and provided with a roughened surface, and means at the end of the handle to engage the roughened surface of the spherical member and retain said member in a desired position, whereby a tool may be maintained at a desired angle with relation to the handle.

3. A dental handpiece comprising a han-

dle having a reduced threaded end, an internally threaded sleeve adapted to engage said end of the handle, said sleeve being provided with a socket and a slot extending from the end of the sleeve down the side thereof, a spherical tool carrying member having a tool engaging projection adapted to be moved into said slot of the sleeve, and means whereby the spherical member may be clamped between the ends of the handle and sleeve against movement, to permit a dental tool to be retained at various angular positions with relation to the handle.

WILLIAM HAROLD MOSLEY.
